[57] CLAIM

The ornamental design for a frame for eyeglasses, as shown and described.

DESCRIPTION

FIG. 1 is a top plan view of a frame for eyeglasses according to my design;
FIG. 2 is a front elevational view thereof;
FIG. 3 is a left side view thereof, the right side view being a mirror image of FIG. 3;
FIG. 4 is a rear elevational view thereof; and,
FIG. 5 is a bottom plan view thereof.

FIG. 1

FIG. 2

FIG. 3

FIG. 4

FIG. 5
